COAL BREAKING MACHINE

Henry Gordon Hope, Swansea, Wales

Application January 24, 1936, Serial No. 60,713
In Great Britain February 2, 1935

7 Claims. (Cl. 83—52)

The present invention concerns improvements in or relating to coal breaking machines, of the type (hereinafter referred to as the type specified) in which a screen is used to convey coal to a breaking device.

It is customary in machines of the type specified to break the coal by means of toothed breaking devices which press the coal on to the screen which latter thus acts as one of the breaking elements. Such an arrangement is apt to result in the production of an unduly large amount of very small coal because when the coal is delivered on to the screen the small pieces sink to the bottom with the large pieces riding on top of them, and consequently the small pieces are crushed to very small pieces between the large pieces and the screen before the pressure is sufficient to break large pieces; if it happens that there are no small pieces under a large piece but the under side of a large piece comprises irregular projections then these projections are apt to be crushed into very small pieces before the main body of the large piece is broken. Such very small coal has a poor market value.

The main object of the present invention is to provide a construction in which these undesirable conditions do not occur at least to any large extent.

One feature of the invention is a coal breaking machine of the type specified comprising a screen, a lower toothed breaking element the teeth of which are arranged to penetrate the screen, and an upper breaking element arranged to press upon and break coal that rests upon the top of the teeth of the lower element while they project above the screen.

The invention will become more fully apparent to those skilled in the art from the following description of one construction of coal breaking machine illustrative of the invention, reference being made to the accompanying drawings, in which:

Fig. 1 is a longitudinal section taken on the line C—D of Fig. 3,

Fig. 2 is a similar view of an additional unit which may be employed with the machine shown in Fig. 1, and

Fig. 3 is a transverse section taken on the line A—B of Fig. 1.

The illustrative construction comprises two cheek members 1 which are spaced apart to constitute a frame having an outlet at the bottom for broken coal and between which at the right-hand end, as seen in Fig. 1, coal to be broken is delivered from a feed chute (not shown). A

vibratory screen 2 is supported between the cheeks 1 on links 3 so that it slopes downwardly from beneath the feed chute to the opposite end of the frame, lateral guides 4 being provided to prevent the coal from falling off the sides of the screen.

Adjacent each end of the screen 2 there is disposed a pair of co-operating breaking elements. Each element comprises a base 5 having several rows of tapered teeth 6 which extend across the width of the screen, the teeth of the lower element of a pair being so disposed that they pass between the longitudinal members 2a of the screen 2 at an area devoid of transverse members 2b when the screen moves to its lowest position. The upper and lower elements are slidably engaged by their ends in guideways 7 formed in the cheeks 1 and extending substantially perpendicular to the plane of the screen 2, the base portions 5 of the lower elements being supported resiliently by means of springs 8 engaging brackets 9 on the cheeks 1. The teeth 6 of the upper element of a pair do not at any time pass through the screen 2 and are preferably arranged to register with the corresponding teeth of the lower element of the pair, the spacings of the teeth on the elements near the lower end of the screen 2 being smaller than those of the elements near the upper end of the screen.

The upper element of each pair of co-operating breaking elements is connected by connecting rods 10 to cranks 11 on a crank shaft 12 extending transversely above and supported by the cheeks 1, each crank shaft carrying a flywheel 13 at one end.

When rotated by suitable means (not shown) the crank shafts 12 cause the upper breaking elements to reciprocate in the guideways 7 and one of said shafts also imparts the necessary vibratory or jiggling movement to the screen 2 by means of link connections 14, shown associated with the right-hand breaking elements in

Fig. 1 and connecting the lower pivoted ends of the connecting rods 10 and links 3. As can be seen from Fig. 3 the connecting rods 10 and links 3 are pivoted to the upper breaking elements 5, 6 and the screen 2, respectively, by means of shafts 15 the lower end of which extends at its ends through slots 16 formed in the cheeks 1.

Due to the connections 14, the screen 2 is oscillated about the pivots for the upper ends of the links 3, this oscillatory movement taking place in timed relation to the reciprocating movements of the upper breaking elements 5, 6, so that the screen is moved forwardly (i. e. to the left in Fig. 1) and upwardly as the upper breaking elements are

40 45 50 55

40 45 50 55

40 45 50 55

moved upwardly. In the course of its forward and upward movement the screen 2 rises above the points of the teeth 6 on the lower breaking elements.

5 The operation is as follows:—Coal is fed through the feed chute (not illustrated) on to the upper end of the screen 2 and by reason of the slope of the screen and the vibratory or oscillatory movement thereof it travels downwardly along the screen. When the coal arrives at the breaking locations, each downward and rearward movement of the screen leaves those pieces of coal which are too large to pass between the teeth 6 of the lower breaking elements straddling the points of the said teeth in position for the upper teeth, which are then descending, to act with full force on these large pieces and break them.

10 The breaking elements then separate and the consequent forward and upward movement of the screen displaces the broken coal towards the lower end of the screen and brings a fresh supply of coal to be broken above the lower breaking elements. During their travel along the 15 screen those pieces of coal which are small enough fall through the screen.

20 In this way the coal is broken without an undue amount of very small pieces.

If desired there could be only one breaking 25 location or more than two breaking locations. In the first case the coal-breaking unit would be of substantially the same construction as the additional unit shown in Fig. 2, and in the second case either such an additional unit may be 30 detachably connected to the main unit shown in Fig. 1 or the main unit may be constructed initially with the required number of breaking 35 locations.

The unit shown in Fig. 2 does not require detailed description as the same reference numerals are employed here as have been used to denote similar parts in Figs. 1 and 3. The upper end of the screen 2 of the additional unit is arranged to extend beneath the lower end of the main screen 2, so that it may collect any coal 40 leaving the latter, and the teeth 6 of the additional breaking elements are more closely spaced than those at the lower location in the main unit.

45 When the coal to be broken is comparatively soft and bulky it is preferred to reciprocate the lower elements of the pairs of co-operating breaking elements oppositely to the upper elements of these pairs, i. e. so that the upper and lower elements of a pair are positively moved towards and away from each other, for example the lower elements being operated by means of connecting rods from additional cranks provided on the crank shafts 12 at 180° from the cranks 50 11 operating the upper elements.

55 It is preferred, in all the coal breaking machines according to this invention, to construct the link connections 3 and 14 in such a manner that they can yield resiliently should pieces of material, such as fragments of castings, which are harder than those materials with which the machines are intended to deal, pass through the 60 breaking locations.

55 What I claim is:—

1. A coal breaking machine comprising co-operating upper and lower toothed breaking elements, a screen located between said elements for supporting and conveying coal, means for producing relative movement of the said elements towards and from each other and means for producing relative movement between the 70

screen and the lower breaking element to cause the teeth of the latter to project through the screen during the periods in which the breaking elements move towards each other.

2. A coal breaking machine comprising co-operating upper and lower toothed breaking elements, an oscillatably mounted screen extending between said elements for supporting and conveying coal, means for reciprocating the upper breaking element towards and from the screen 10 and means for oscillating the screen in timed relation to the movements of the upper breaking element to cause the teeth of the lower breaking element to project through the screen during each movement of the upper breaking 15 element towards the latter.

3. A coal breaking machine comprising co-operating upper and lower toothed breaking elements, a screen extending between said elements for supporting and conveying coal, means for reciprocating the upper breaking element toward and from the screen and means for moving the screen to a lower level than the points of the teeth on the lower breaking element each time that the upper breaking element is moved towards the screen.

4. A coal breaking machine comprising a screen for supporting and conveying coal, an upper breaking element reciprocably mounted above a portion of said screen, teeth secured on said element with their operative points directed downwardly, a lower breaking element reciprocably mounted beneath the said screen portion, teeth secured on said lower breaking element with their operative points directed upwardly, means for causing relative movement of the upper and lower breaking elements towards and from each other and means for moving the screen to a lower level than the operative points of the teeth of the lower breaking 35 element as the distance between the latter and the upper breaking element is reduced.

5. A coal breaking machine comprising an inclined screen for supporting and conveying coal, a lower breaking element having teeth directed 45 upwardly towards the screen, means for producing relative oscillatory motion between the said screen and lower breaking element, such motion including a component whereby the screen is moved substantially in the direction of its length 50 and a component whereby the screen and breaking element have a relative movement substantially in the direction of the teeth of the said element so that the said teeth periodically project through the said screen, an upper breaking 55 element having teeth directed towards those of the lower breaking element and means for moving the said upper element towards the screen as the teeth of the lower element project therethrough.

6. A coal breaking machine comprising an upper toothed breaking element, an inclined screen arranged beneath said element for supporting and conveying coal, means for oscillatably supporting said screen, means for reciprocating the upper breaking element towards and from the screen, an operative connection from the said element to the screen for causing oscillatory movement of the latter having a downward component upon each movement of the said element 70 towards the screen, and a lower toothed breaking element arranged beneath the screen so that its teeth project through the latter upon each downward movement thereof.

7. A coal breaking machine comprising a 75

frame, a screen for supporting and conveying coal, means supporting the screen from the frame for oscillation downwardly and upwardly in the direction of its length, an upper toothed breaking element mounted in the frame for reciprocation towards and from the screen, means for reciprocating said element, an operative connection from the said element to the screen to

cause a downward oscillation thereof at each movement of the element towards the screen and a lower toothed breaking element located beneath the screen so that its teeth project therethrough at each downward oscillation of 5 the screen.

HENRY GORDON HOPE.
